(57) CLAIM

The ornamental design for a toothbrush head with double sided bristles, as shown and described.

DESCRIPTION

FIG. 1 is a top perspective view of a toothbrush head with double sided bristles, showing my new design.

FIG. 2 is a front elevation view thereof;

FIG. 3 is a top plan view thereof; and,

FIG. 4 is a bottom plan view thereof.

The broken lines in the drawings depict portions of the toothbrush head with double sided bristles that form no part of the claimed design.
